UNITED STATES PATENT OFFICE.

ROBERT H. ANDERSON, OF SAN DIEGO, CALIFORNIA, ASSIGNOR TO RUTH B. ANDERSON,
OF SAN DIEGO, CALIFORNIA.

DEVICE FOR SHIFTING ARTICLES THROUGH A NARROW DOORWAY.

1,086,744.

Specification of Letters Patent.

Patented Feb. 10, 1914.

Application filed February 1, 1912. Serial No. 674,816.

To all whom it may concern:

Be it known that I, ROBERT H. ANDERSON, a citizen of the United States, and a resident of San Diego, in the county of San Diego 5 and State of California, have invented certain new and useful Improvements in Devices for Shifting Articles Through a Narrow Doorway, of which the following is a specification.

- 10 My invention relates to a device which is placed in a door-way and upon which may be mounted a dresser, stove, bed or other piece of furniture which remains thereon to be shifted back and forth for use in certain 15 positions in either of two adjacent rooms as desired, and which is so constructed that it is adapted to a variety of different forms and shapes of furniture, and the objects are first, to provide a device of this character 20 which is simple and economical of construction, easily installed, easily adjusted and to which an article may be readily attached; second, to provide a device of this character adapted to shift an article through a 25 doorway of a minimum width; third, to provide a device of this character which requires little care in operating it so that by merely shoving on the article, the device will shift it into its proper place. 30 With these and other objects in view as will appear, my invention consists of certain novel features of construction, combination and arrangement of parts, as will be hereinafter described in detail and particularly set forth in the appended claims, reference being had to the accompanying drawings and to the characters of reference thereon, which form a part of this specification, in which:—
- 35 Figure 1 is a plan view of my device shown in connection with an article of furniture shown by dotted lines in position in the doorway between two rooms, Fig. 2 is a side elevational view of the same, Fig. 45 3 is a sectional and plan view of a partition with a doorway between two rooms and showing my device in its position in one of the rooms, Fig. 4 is a similar view showing the device in position in the other room, 50 and Fig. 5 is a similar view showing the device in position when moving from one room to the other.

Similar characters of reference refer to similar parts throughout the several views.

- 55 The bearings 1 and 2, supports 3 and 4,

connection piece 5, bars 6, 7, 8 and 9, stops 10 and 11, spring 12 and post 13 constitute the principal parts of my device.

The bearing 1 is attached at a suitable height to the side of the door casing approximately at the middle. The bearing 2 is a thrust bearing preferably a ball-bearing and is mounted on the floor directly below bearing 1. In these bearing pieces 1 and 2 is mounted a post 13, upon which are rigidly mounted supports 3 and 4. These supports 3 and 4 are adapted to swing with said post in said bearings. Upon the extended end of said support 4 is mounted connection piece 5, which is preferably made of angle iron, and which is provided with screws adapted for the attachment to it of any article which it is desired to shift. The support 3 is attached to the article to be shifted near its upper edge by means of a U-shaped piece 3^a, pivotally mounted on the extended end of the support 3, and its ends adapted to be attached to the article to be shifted, by means of screws.

Attached to the ends of the connecting piece 5 are bars 6 and 9 pivotally connected thereto. Extending some distance from said pivotal points and pivotally connecting with the extended end of said bar 6 is bar 7 and similarly connecting with the extended end of bar 9 is bar 8. The other ends of bars 7 and 8 are pivotally joined and pivotally attached to the floor at a point to provide the proper shift. Placed in the floor at the proper point to provide the proper shift are also stops 10 and 11, which extend up from the floor a sufficient distance to engage respectively with the bars 7 and 8, when they are in certain relative positions when the device is shifted. The spring 12 is rigidly attached to connection piece 5 and is adapted to engage with bar 7 and support 4 when they are in certain relative positions to said connection piece 5, and to engage with bar 9 when the connection piece 5 is swung to the outside of the aperture. It is for the purpose of holding bars 6, 7, 8 and 9 in such a relative position to one another, as to prevent the mechanism from stopping on a dead center.

Though I have shown and described a particular construction and arrangement of parts, I do not wish to be limited to this particular construction and arrangement, but desire to include in the purview of my

invention, the construction and arrangement substantially as set forth in the appended claims.

It will be readily seen that with the device as shown and described, there is provided a device to which articles of furniture and the like may be permanently attached so as to be shifted back and forth from one room to another through a narrow aperture or doorway; that the position of the stops in the floor may be changed for adjusting the device to different shifting positions; that the construction of the device provides for the shifting of the article edgewise, as it passes through the aperture or doorway, thus allowing it to be of a minimum width; that the device is simple of construction and easily installed and operated.

Having thus described my invention, what I claim as new and desire to secure by Letters Patent is:—

1. In combination with a wall having an opening, a bed of greater width than said opening attached to a transversely movable vertical axis arranged adjacent to one side of said opening and intermediate between the sides of the bed.
2. In combination with a wall having an opening, a bed comprising a part attached to a transversely movable vertical axis arranged adjacent to one side of said opening and intermediate between the sides of the bed and a collapsible part adapted to swing upward upon a horizontal axis.
3. In combination with a wall having an opening, a bed of greater width than said opening, adapted to be folded to a vertical position having a pivotal support at one side of said opening by transversely movable pivots located sufficiently near the central vertical axis of the head of the bed to permit the bed to swing horizontally therethrough when folded.
4. A device for facilitating the shifting of articles through a narrow aperture comprising a post pivotally mounted to one side of said aperture, supports mounted on said post near the top and bottom, a supporting bar mounted on one of said supports adapted to increase its supporting surface, means on the other support adapted to facilitate the connection of said support to an article of furniture, a plurality of bars pivotally connected together and to each end of said supporting bar and means adapted to engage with a portion of said pivoted bars.
5. A device for facilitating the shifting of articles through a narrow aperture com-

prising a post pivotally mounted to one side of said aperture, supports mounted on said post, a horizontal bar mounted on one of said supports, a plurality of bars pivotally connected together and to said horizontal bar, stop means mounted in the floor of said aperture adapted to engage with a portion of said pivotally connected bars adapted to facilitate the shifting of said horizontal bar endwise through the aperture, and a spring means mounted on said horizontal bar adapted to engage with two of said pivotally connected bars to facilitate the operation of said device.

6. A device for facilitating the shifting of articles through a narrow aperture comprising a bearing mounted on the side wall of said aperture, a thrust bearing mounted in the floor of said aperture, a post pivotally mounted on said bearings, supports rigidly mounted near the upper and lower ends of said posts, a horizontal bar mounted on the lower support adapted to increase its supporting surface, means mounted on the upper support adapted to facilitate its connection to an article of furniture, a plurality of bars pivotally connected to each other and in connection with said horizontal bar and a plurality of stop means mounted in the floor adapted to engage with a portion of said pivotally connected bars when in certain positions adapted to change the relative positions of said bars.

7. A device for facilitating the shifting of articles through a narrow aperture comprising a bearing rigidly attached to the side walls of the aperture, a thrust bearing mounted on the floor in said aperture, a post pivotally mounted in said bearing, supports rigidly mounted one near the top and the other near the bottom of said post, a horizontal bar mounted on said supports adapted to increase the supporting surface and to facilitate its connection to an article of furniture, a plurality of bars pivotally connected to each other and in connection with said horizontal bar, and a plurality of stops mounted in the flooring all adapted to facilitate the shifting of said horizontal bar endwise through the aperture.

In testimony whereof, I have hereunto subscribed my name in the presence of two subscribing witnesses.

ROBERT H. ANDERSON.
